UNITED STATES PATENT OFFICE.

CASEY MALLERY, OF NATCHEZ, MISSISSIPPI.

RAZOR.

933,317.

Specification of Letters Patent. Patented Sept. 1, 1909.

Application filed December 4, 1908. Serial No. 465,985.

To all whom it may concern.

Be it known that I, CASEY MALLERY, a citizen of the United States, residing at Natchez, in the county of Adams and State of Mississippi, have invented new and useful Improvements in Razors, of which the following is a specification.

This invention relates to razors of that type known as the safety razor, and the object of the invention is to provide a razor of this character provided with a handle and a shank pivoted to said handle, the shank being provided with a guard adapted for the reception of a removable razor blade, said blade being retained in position upon the guard through the medium of a resilient clamping element, and the shank being provided with a projecting finger portion whereby the blade may be swung upon the handle and retained in proper position for use by the operator.

With the above and other objects in view, which will appear as the description progresses, the invention resides in the novel construction and arrangement of parts hereinafter fully described and claimed.

In the accompanying drawing there has been illustrated a simple and preferred embodiment of the invention, and in which: Figure 1 is a perspective view of the improved razor. Fig. 2 is a sectional view upon the line 2—2 of Fig. 1. Fig. 3 is a side elevation of the end of the shank upon which is positioned the clamping member of the blade. Fig. 4 is a side elevation of the blade. Fig. 5 is a perspective view of the clamping member. Fig. 6 is a detail perspective view of the outer end of the shank upon which is integrally formed the razor guard.

In the drawing the numeral 1 designates a razor handle of the ordinary construction, this handle comprising a pair of spaced members between which is adapted to be positioned the blade of the razor when the latter is in closed position. Pivotaly connected, as at 2, between the spaced members of the handle 1 is a shank 3, also of the ordinary construction and having, what may be termed a finger hold extending rearwardly beyond its pivot, and through the medium of which the shank 3 may be adjusted at any desired angle in relation to the handle 1. The shank 3, in the present instance, is provided with a cut away portion or pocket 5, and has its outer surface formed

with a right angular flattened guard 6. This guard 6 has one of its longitudinal edges provided with spaced upwardly inclined teeth or guard members 7 and the outer transverse edge of the guard is bent downwardly at a substantially right angle to provide a wall 6'. The longitudinal edge of the guard opposite that provided with the teeth 7 has its outer corner cut away as designed by the numeral 6" so as to position the vertical edge of the offset 6' directly in a line with the inner face of the pocket 5.

The numeral 8 designates the razor blade employed with the present device. This blade 8 is preferably V-shaped in cross section, as clearly illustrated in Fig. 2 of the drawing, and has its side, opposite that of its cutting edge provided with outwardly extending lugs or projections 9, which are adapted to engage with the pocket 5 and the wall 6" of the offset side 6' of the guard 6, thus providing a means whereby the blade may be positioned upon the guard 6.

The numeral 10 designates the resilient clamping member of the device. This member 10 comprises an upper longitudinally extending lip or face 11 and a lower longitudinally extending face 12. The said faces being divided from each other through the medium of the integrally formed wall 13. The faces 11 and 12 are arranged at an angle with each other to correspond to the cross sectional V-shaped blade 8 and are adapted when positioned upon the blade and guard 90 to effectively secure the said blade rigidly upon the guard.

From the above description, taken in connection with the accompanying drawing, it will be noted that I have provided an extremely simple and comparatively cheap article for the purpose set forth, one which incorporates all the advantages of the old style razor whereby the shank and handle may be adjusted in relation to each other so as to accommodate the blade to the use of the operator and which provides detachable blades which may be easily and quickly positioned upon the guard or removed therefrom as desired.

Having thus fully described the invention what is claimed as new is:

In a razor of the class set forth, the combination with a handle, a shank pivotally connected with the handle, said shank having an offset guard member provided with spaced teeth and having a pocket adjacent

the guard member, the guard having its outer end provided with an offset wall, a blade provided with offsets adapted to be positioned upon the guard and to have its offset portions engaging the pocket of the shank and the edge of the offset portion of the guard, and a resilient clamping member comprising a single element having upper

and lower faces adapted to engage the guard and the blade.

In testimony whereof I affix my signature in presence of two witnesses.

CASEY MALLERY.
